UNITED STATES PATENT OFFICE.

RAY FAMULENER, OF SALT LAKE CITY, UTAH.

COMBINATION INKWELL AND PENRACK.

Application filed August 21, 1922. Serial No. 583,215.

To all whom it may concern:

Be it known that I, RAY FAMULENER, a citizen of the United States, residing at Salt Lake City, in the county of Salt Lake 5 and State of Utah, have invented certain new and useful Improvements in a Combination Inkwell and Penrack, of which the following is a specification.

This invention relates to ink wells, and 10 the primary object of the invention is to provide a novel cover for ink wells embodying a pen holder rack, the cover being so constructed that the same will automatically move to its open position when the pen holder is removed from the rack, and automatically returned to its closed position when the pen holder is placed upon the rack.

Another object of the invention is to 20 provide a novel means for forming the mouth of the ink well, and novel means of associating the cover with the well for co-operation with the mouth of the well, the cover and mouth forming a substantially 25 air tight closure, to prevent the evaporation of the ink and to prevent the entrance of dust and the like into the ink well.

A further object of the invention is to 30 provide an improved barometric ink well embodying a main supply reservoir and the pen dipping well, the main reservoir forming means for maintaining a constant level 35 of ink in the pen dipping well, the well being of novel configuration to prevent the soiling of the pen holder when the pen is dipped into the well.

A further object of the invention is to 40 provide a novel means for constructing the well, so as to facilitate the filling of the reservoir, and to facilitate the insertion of the pen into the well, the well being so inclined that the pen can be placed therein when the same is held in a normal writing 45 position.

A further object of the invention is to 50 provide a novel cover for barometric ink wells embodying a pair of side arms pivotally secured intermediate their ends to the opposite sides of the well, the arms being 55 connected together by a cross plate which acts as a cover for the mouth of the well, the forward ends of the arms acting as a rack for pen holders, which tends to move the cover plate over and down onto the mouth 60 of the well, the rear terminals of the arms acting as weights for moving the cover

plate up and away from the mouth of the well when the pen holder is moved off of the forward ends of the arms.

A still further object of the invention 60 is to provide an improved ink well cover of the above character, which is durable and efficient in use, one that is simple and easy to manufacture, and one which can be placed upon the market at a reasonable cost. 65

With these and other objects in view, the invention consists in the novel construction, arrangement and formation of parts as will be hereinafter more specifically described, claimed and illustrated in the accompanying drawings, forming a part of this specification, in which drawings:

Figure 1 is a perspective view of the improved ink well and cover, showing a pen holder positioned on the arms or pen rack 70 and normally holding the cover in its closed position.

Figure 2 is a side elevation of the improved ink well and cover, showing the pen holder removed from the arms or pen 80 rack and the cover swung back to its open position.

Figure 3 is a top plan view of the improved ink well and cover, showing the cover in its open position.

Figure 4 is a longitudinal section through the improved device, taken on the line 4-4 of Figure 3.

Figure 5 is a transverse section through the improved device, taken on the line 5-5 90 of Figure 4.

Figure 6 is an enlarged detail transverse vertical section showing the means of attaching the cover to the side of the ink well.

Referring to the drawings in detail, 95 wherein similar reference characters designate corresponding parts throughout the several views, the letter A generally indicates the improved ink well, and B, the novel cover therefor.

The improved ink well A embodies the barometric principle and is preferably formed of glass, but it is of course apparent that other suitable material may be used. The ink well A embodies a main body 10 and a forwardly extending extension 11 which is of less height than the main body portion 10. The main body portion 10 is provided with an enlarged internal chamber 12 which forms the main reservoir for the ink. The extension 11 is provided with a pen dipping well 13 which opens out of the 110

upper end of the extension and this well is of novel shape and forms an important part of this invention.

As shown, this well is inclined inwardly and downwardly from its upper end toward its lower end and is connected with the lower end of the reservoir 12 by means of a downwardly inclined forwardly extending port 14. The well 13 extends slightly below this port. As clearly shown in Figures 4 and 5 of the drawings, the well 13 is of a substantially acorn shape, and the well bulges outwardly or is enlarged at its central portion as at 15, and then gradually tapers inwardly toward its bottom end and terminates in a point as indicated by the reference character 16. As stated, the upper end of the well opens out through the upper end of the extension 11, and this end forms a relatively large opening so as to permit the ready insertion of the pen into the well. Owing to the inclination of the well, the pen of course can be inserted therein when held in a natural writing position by the user. The forward portion of the upper wall of the extension 11 is inclined downwardly as at 17, and of course the well terminates in the same plane therewith. Around the edge of the well is placed the upstanding lip 18 for a purpose which will hereinafter more fully appear, and the inner surface of this lip 18 is inclined inwardly and downwardly as at 19 in order to facilitate the insertion of the pen into the well and to form a tight joint with the stopper 27' which will be hereinafter more fully described. This lip 18 terminates at the rear end of the mouth of the well.

When it is desired to fill the reservoir 12 of the ink well, the well is tipped back and laid on its rear wall. The ink can now readily be introduced into the reservoir through the well 13 and owing to the downward and inward inclination of the well, the filling of the reservoir is considerably facilitated. After the reservoir 12 has been completely filled, the ink well is turned back to its normal position and the ink will flow through the port 14 into the well to a certain level, and the ink will be always maintained at this level until the ink has been exhausted from the reservoir. Owing to the downward inclination of the port 14, all of the ink will readily drain from the reservoir.

The edges of the ink well can be bevelled as at 20 in order to eliminate the presenting of sharp edges in order to prevent the cutting of the hands of the user.

The improved cover R comprises side plates 25 and 26 which are constructed identically the same, and the transverse connecting cover plate 27. These side plates 25 and 26 are rockably mounted at a point intermediate their ends and adjacent to their

lower edges upon suitable bolts or screws 28, which are threaded in suitable sockets 29 formed in the sides of the ink well A as clearly shown in Figures 1, 2, and 6 of the drawings. Suitable washers 30 can be placed upon the screws 28 intermediate the side walls of the ink well A and the side plates 25 and 26. Each of the side plates include the forwardly extending arcuate arms 31 which extend beyond the forward wall of the ink well A, and these arms constitute a rack for the pen holder. In rear of the pivot pins or screws 28, the arms are enlarged or provided with substantially circular extensions 32, which constitute weights for normally swinging the arms upwardly when the pen holder is removed from the rack. Directly above the pivot point or bolts 28, and intermediate the arms 31 and the circular extensions 32, the side plates 25 and 26 are provided with upwardly extending arms 33, and these arms extend above the upper surface of the extension 11 of the ink well A and have connected thereto the cover plate 27 heretofore mentioned. It can be seen that the side plates 25 and 26 and the cover plate 27 can be formed of a single piece of sheet metal if so desired. This cover plate 27 is adapted to engage the upper edges of the lips 18 and form substantially a fluid tight closure therefor, in order to prevent the entrance of air, dust and the like into the ink well 13. In order to provide a further and positive means for forming a fluid tight closure for the ink well, the cover plate 27 has secured thereto in any preferred manner a stopper 27' formed of rubber, cork, or the like, and is of a size and shape to fit snugly within the bevelled inside 19 of the lip 18 and extends far enough back to come even with the ends of the lip. The lips 18 being bevelled on the inside and open at the rear, and the stopper being made to fit the same will permit the cover and stopper to be raised with very little friction.

In use of the improved ink well, a pen holder C is placed upon the arms 31 constituting the pen rack, and the weight of the pen holder C will overcome the weight of the weights or circular extensions 32, and thus swing the cover plate 27 forwardly and downwardly onto the lips 18 and bring the stopper 27' into intimate contact with the inner surface of the lip 18, and thus prevent the entrance of dirt and the like into the pen dipping well 13. Now, when it is desired to use the well, the pen holder C is removed from the arms 31, and the weights or central extensions 32 will then tend to rock the side plates 25 and 26 downwardly, thus moving the cover plate 27 upwardly and rearwardly from off of the lips 18, permitting the ready insertion of the pen holder into the pen dipping well 13.

From the foregoing description, it can be seen that an improved ink well has been provided, embodying a novel cover, which is automatically held in its closed position by the weight of the pen holder, and which will automatically move to its open position when the pen holder is removed for writing purposes.

Changes in details may be made without departing from the spirit or scope of this invention; but,

I claim:

1. An ink stand including a pen dipping well having the upper end thereof terminating in an inclined plane in relation to the horizontal, a cover for said pen dipping well including a pair of side plates, and a transversely extending connecting cover plate, a stopper carried by said cover plate, means rockably connecting the side plates intermediate their ends to the sides of the ink stand, forwardly extending pen holder supporting arms formed on the side plates arranged to rock the side plates and move and hold the cover plate over the open end of the well when a pen holder is placed therein, and weights formed on the rear ends of the side plates for normally holding and moving the cover plate away from the open end of the well when the pen holder is removed from off of said pen holder supporting arms.

2. An ink stand including a pen dipping

well having the upper open end thereof terminating at an inclined plane in relation to the horizontal, a lip extending around the opening of the inclined well having its upper end terminating at an inclined plane in relation to the horizontal, a cover for the ink well including a pair of side plates and a transversely extending cover plate connected with the side plates, means rockably connecting the side plates at a point intermediate their ends and adjacent to their lower edges to the sides of the ink stand, forwardly extending arcuate arms formed on the plates and arranged to extend beyond the forward end of the ink stand and forming supports for pen holders, weights formed on the rear terminals of the side plates in rear of the pivot points thereof for rocking the side plates when the pen holder is removed from off of the pen holder supporting arms, upwardly extending arms formed on the side plates intermediate the arms and weights and above said pivot points and supporting said cover plate, the cover plate being adapted to be moved forwardly and downwardly onto the inclined faces of the lips when the pen holder is placed upon the arms, the weights being adapted to move the cover plate upwardly and rearwardly from off of the lips when the pen holder is removed from off of the arms.

RAY FAMULENER.
